UNITED STATES PATENT OFFICE.

GEORGE C. HALBLAUB, OF CHICAGO, ILLINOIS.

SAFETY-STOP FOR ELEVATORS.

SPECIFICATION forming part of Letters Patent No. 337,398, dated March 9, 1886.

Application filed October 19, 1883. Serial No. 109,504. (No model.)

To all whom it may concern:

Be it known that I, GEORGE C. HALBLAUB, a citizen of the United States, and a resident of Chicago, in the county of Cook and State 5 of Illinois, have invented a new and useful Improvement in Safety-Stops for Elevators; and I do hereby declare the following to be a full, clear, and exact description of the same, reference being had to the accompanying 10 drawings, forming a part of this specification.

My invention relates to improvements in that class of stopping mechanism employed to check and stop too sudden descent of the cab or platform of passenger or other elevators; and my improvement has for its objects, first, to furnish a compact device capable of ready insertion or application to the lower end of the stile of the elevator, so as to act as a guide for the same at such point; second, 15 to provide a cheap, strong, and effective device which engages both sides of the guide-strip of the elevator-well, so as to arrest with great certainty the sudden downward movement of the cab upon the parting of the elevator-cable, or from other accidental causes. 20 I attain such objects by the mechanism illustrated in the accompanying drawings, in which—

Figure 1 is a perspective view of my improved device, looking from the rear; Fig. 2, 30 a vertical section showing the safety dogs or catches in their "up" or "engaged" position. Fig. 3 is a similar view showing the same in their "down" or "disengaged" position. Fig. 4 is a front elevation, with parts in section, of an elevator-cab, showing the arrangement of my improved stop and its operating connections with the elevator-cable.

As shown in the drawings, the housing or 40 casing consists of a base plate or flange, A, for engagement under the end of the cab stile or platform F, and vertical guide-jaws B B, which embrace the guide-strip G for the elevator, so as to form a guide for the lower end 45 of the elevator-cab. At each side of the guide-jaws are formed chambers to receive the duplicate dogs or catches C, journaled at c, as shown, with their engaging ends pointing toward each other. These dogs or catches 50 are lifted from the inclined position shown in

Fig. 3 into a nearly horizontal position, as shown in Fig. 2, by being connected to a vertically-moving cross head or plate, D, provided with elongated inclined slots d, that receive pins c' upon the dogs, as shown, the 55 construction being such that in a downward movement of the head D the slots will tend to force the dog away from the guide-strip G of the elevator, and vice versa upon an upward movement of said head.

The movement of the plate D, with the consequent application of the safety-catches, may be controlled by the automatic governor usually employed upon passenger-elevators to prevent a too rapid descent of the same, 65 or by means of the ordinary safety mechanism which applies the safety-check upon the parting of the elevator-cable, as represented in Fig. 4, in which E is the vertical rod by which motion is communicated to the cross-head D from the spring-operated cable-stirrup E' through pivoted lever e.

My improved catch mechanism can be used in connection with either mechanism, the cross head or plate D being provided with a horizontal stem, d', to which is attached the vertical operating-rod E, extending to governing mechanism.

I prevent any rocking motion of the cross-head D by forming the portion of the stem d' 80 that passes through the guide-slot a of an elongated form, as shown in dotted lines in Figs. 2 and 3, and by this means hold the dogs or catches, when in their down position, from any accidental engagement with the guide-strip G.

Having thus fully described my invention, what I claim, and desire to secure by Letters Patent, is—

1. A safety-catch for elevators, consisting 90 of a casing or housing having a flange portion, A, guide-jaws B B, and pivoted dogs or catches C, with the cross-head D, receiving motion from the safety mechanism of the elevator, substantially as described, and for the 95 purpose set forth.

2. A safety-catch for elevators, consisting 90 of a casing or housing having flange portion A, and guide-jaws B B, in combination with the pivoted dogs or catches C C, having pins c' c', 100

and the cross-head D, having inclined slots d and d , substantially as described, and for the purpose set forth.

3. In a safety-catch for elevators, essentially as herein described, the casing or housing for the stop dogs or catches, provided with an elongated guide-slot, a , in combination with the cross-head D, having a stem, d , of an elongated

gated form, moving in said slot, substantially as described, and for the purpose set forth.

In testimony whereof, witness my hand this 29th day of September, 1883.

GEORGE C. HALBLAUB.

In presence of—

N. B. NASH,
H. D. SMALLEY.
